US00D736023S

(12) **United States Design Patent**
Rawls-Meehan

(10) **Patent No.:** **US D736,023 S**
(45) **Date of Patent:** **** Aug. 11, 2015**

(54) **ADJUSTABLE BED**(71) Applicant: **ASCION, LLC**, Bloomfield Hills, MI (US)(72) Inventor: **Martin B. Rawls-Meehan**, Franklin, MI (US)(73) Assignee: **ASCION, LLC**, Bloomfield Hills, MI (US)(***) Term: **14 Years**(21) Appl. No.: **29/508,204**(22) Filed: **Nov. 4, 2014**

Primary Examiner — Janice Seeger(74) *Attorney, Agent, or Firm* — Gifford, Krass, Sprinkle, Anderson & Citkowski, P.C.; Douglas L. Wathen(57) **CLAIM**

The ornamental design for an adjustable bed, as shown and described.

DESCRIPTION

FIG. 1 is a perspective view of an adjustable bed in accordance with the present invention; and,
FIG. 2 is a side perspective view of the adjustable bed of FIG. 1.

The broken lines are for environmental purposes only and form no part of the claimed design.
